UNITED STATES PATENT OFFICE.

BENJAMIN PHILLIPS, OF TRENTON, NEW JERSEY.

PUDDLING-FURNACE.

SPECIFICATION forming part of Letters Patent No. 229,177, dated June 22, 1880.

Application filed September 24, 1879.

To all whom it may concern:

Be it known that I, BENJAMIN PHILLIPS, of Trenton, in the county of Mercer and State of New Jersey, have invented an Improvement 5 in Puddling-Furnaces, of which the following is a specification.

This invention is designed to provide what may be properly termed a "combined puddling and crucible furnace;" in other words, a 10 furnace in which the operations of puddling iron and of melting steel or other metallic substances in crucibles may be simultaneously carried on.

The invention comprises a fire-box having 15 benches placed respectively at its front and back, and with doors placed coincident with said benches in such a manner that crucibles may be placed upon the benches to be used in melting metal or any desired or suitable 20 material by means of the same flame used or utilized in the operation of puddling.

The invention also comprises the novel combination of the puddling-chamber with the parts aforesaid.

25 By means of the combinations just hereinbefore specified the apparatus may be used for the double functions of an ordinary puddling-furnace and of a furnace for melting steel or other materials in crucibles, the operations 30 of puddling and melting in crucibles being carried on either simultaneously or singly, as the exigency of the work may require.

Figure 1 is a vertical longitudinal section, Fig. 2 a horizontal section, and Fig. 3 a vertical transverse section, of an apparatus made 35 according to my said invention.

A is the fire-box of the puddling-furnace, and B that portion of said furnace which receives and holds the molten iron during the 40 puddling operation, these parts and those of their accessories essential or relating particularly to the puddling being of any ordinary or suitable construction, and consequently requiring no detailed description here.

Provided within the fire-box A are one or 45 more benches for sustaining crucibles in a position calculated to expose them to the most effective action of the flame or incandescent fuel in the fire-box. Preferably there are two 50 of these benches, as represented in Figs. 1 and 2 and indicated by the reference letters C C, there being one at the back of the fire-box—that is to say, at the side farthest from B—and the other at the front or opposite side of said fire-box. In the wall of the fire-box, and coincident with the adjacent ends of the benches C C, are openings provided with doors D D, and through which the crucibles indicated at 55 a may be placed upon or withdrawn from the benches by means of the appliances ordinarily 60 used for lifting and moving crucibles.

In the use and employment of the apparatus the operation of puddling proceeds in the usual way, simultaneously with which the contact of the flame with the crucibles on the 65 benches C C, together with the intense heat radiated or emitted from the incandescent fuel, is sufficient (without in the least impairing the efficiency of the puddling operation) to heat the crucibles to any degree required for melting their contents of steel or other suitable 70 metallic or other material.

What I claim as my invention is—

1. The fire-box having the benches C C placed respectively at its front and back, and 75 with the doors B D placed coincident with said benches, all substantially as and for the purpose herein set forth.

2. The combination of the chamber or portion A of a puddling-furnace with the fire-box 80 having the benches C C placed respectively at its front and back, and the doors B D placed coincident with said benches, all substantially as and for the purpose herein set forth.

BENJAMIN PHILLIPS.
